[57] CLAIM

The ornamental design for a compact disc display, as shown and described.

DESCRIPTION

FIG. 1 is a perspective of a compact disc display showing our new design;

FIG. 2 is a front elevational view, the rear being identical thereto;

FIG. 3 is a left side elevational view, the right side being identical thereto;

FIG. 4 is a top plan view thereof;

FIG. 5 is a bottom plan view thereof;

FIG. 6 is a front elevational view of a second embodiment of the compact disc display shown in FIG. 1; the rear being identical thereto;

FIG. 7 is a front elevational view of a third embodiment of the compact disc display shown in FIG. 1; the rear being identical thereto;

FIG. 8 is a front elevational view of a fourth embodiment of the compact disc display shown in FIG. 1; the rear being identical thereto;

FIG. 9 is an enlarged cross sectional view of a shelf taken along the center;

FIG. 10 is a perspective view of a fifth embodiment of the compact disc display shown in FIG. 1;

FIG. 11 is a front elevational view, the rear being identical thereto;

FIG. 12 is a top plan view thereof;

FIG. 13 is a bottom plan view thereof;

FIG. 14 is a front elevational view of sixth embodiment of the compact disc display shown in FIG. 1, the rear being identical thereto;

FIG. 15 is a front elevational view of seventh embodiment of the compact disc display shown in FIG. 1, the rear being identical thereto; and,

FIG. 16 is a cross sectional view taken along line 16—16 of FIG. 14.
